UNITED STATES PATENT OFFICE.

LOUIS TREDE, OF DURANT, IOWA.

ELECTRIC ALARM-CLOCK.

No. 838,918.

Specification of Letters Patent.

Patented Dec. 18, 1906.

Application filed June 15, 1906. Serial No. 321,861.

To all whom it may concern.

Be it known that I, LOUIS TREDE, a citizen of the United States, residing at Durant, in the county of Cedar and State of Iowa, have ⁵ invented certain new and useful Improvements in Electric Alarms, of which the following is a specification.

My invention relates to improvements in electric clock-alarms, and refers to a device of ¹⁰ this character which may be readily attached to any clock of ordinary construction.

The object of my invention is the provision of an alarm which will operate with precision, which may be easily regulated or set ¹⁵ for the proper time, and which will be thoroughly reliable and practical.

Another object of the invention is to provide an electric alarm which will operate with economy and will be of simple, durable, and ²⁰ inexpensive construction.

With these and other objects in view my invention consists of a dial, an alarm-hand mounted thereon, an insulated contact-ring on the dial, a contact spring on the alarm-hand adapted to contact the ring, a clock-hand provided with an insulated point to cause contact of the contact-spring and ring, and an electric circuit including an alarm having as its terminals the alarm-hand and ²⁵ the contact-ring.

My invention further consists of an electric alarm embodying certain other novel features of construction, combination, and arrangement of parts, substantially as disclosed ³⁵ herein.

Figure 1 is a front or face view of a clock having my improved electric alarm applied thereto. Fig. 2 is a sectional view of the clock-face on the line 2 2 of Fig. 1. Fig. 3 is ⁴⁰ a detail view of the clock-hand carrying the means for closing the electrical circuit. Fig. 4 is a plan or diagrammatical view of the wiring system.

In the drawings, the numeral 1 designates ⁴⁵ a clock of ordinary construction provided with the usual dial-plate 2. Centrally mounted in the dial-plate is a bushing or sleeve 3, of rubber, paper, or any other suitable insulating material. The bushing projects slightly beyond the face of the dial and is provided in its upper portion with an annular groove or channel 4, in which is seated or secured the contact-ring 5. This ring forms one terminal of the electric circuit and is suit-

ably connected by the wire 6 to one pole of ⁵⁵ the battery 8. A plate or disk 7, formed with the integral depending lugs 9, is secured upon the face of the dial by the studs or fastenings 10. A second disk 11 is mounted upon the stationary disk and secured thereon ⁶⁰ by means of the inturned edges or flange 12, which frictionally bind against the edge of the stationary disk. The edge of the movable disk may be corrugated or knurled, as shown, so as to afford a ready hold for rotating the same. Mounted upon the movable disk or formed integral therewith is a pointer or hand 12', which I will designate the "alarm-hand." Secured near the outer end of the said alarm-hand is a spring-tongue 13, the inner ⁷⁰ end of which extends over the contact-ring.

Upon the outer end of the arbor 14 is mounted the usual hour-hand 15, at the inner end and under face of which is secured a block of insulating material 16, in which is ⁷⁵ secured one end of the spring 17. This spring is preferably formed with a coil or loop 18 intermediate its length and a lower depending free arm 19, adapted to depress the contact-spring 13 when the hour-hand is ⁸⁰ in the proper position.

A switch 20 is conveniently located upon the exterior of the clock-case, and extending from one point of the switch is a wire 21, which preferably leads direct to the stationary disk on the dial-plate, although this wire may simply be grounded on the movement of the clock. From the other point of the switch a conductor 22 leads to an alarm-bell 23, which may be located in the clock-case or ⁸⁵ elsewhere. A wire 24 leads from the opposite terminal of the bell to the return-pole of the battery, and thus completes the circuit. ⁹⁰

In the operation of the alarm the movable disk on the clock-dial is rotated until the ⁹⁵ alarm-hand registers with the proper hour or fraction of an hour on the dial. When the hour-hand reaches the time at which the alarm is set, the insulated point or spring on the hour-hand depresses the contact-spring ¹⁰⁰ 13 and causes it to engage the contact-ring 5. The electrical circuit is then closed, and the path of the current is as follows: from the positive pole of the battery, through wire 6 to the insulated ring on the dial-plate, from the ¹⁰⁵ ring to the contact-spring 13 and alarm-hand and thence by the wire 21 to the switch 20, wire 22, alarm 23, and return-wire 24, back

to the opposite pole of the battery. The length of the depressing-point on the hour-hand may be changed to suit various conditions, so as to ring the alarm for a long or a 5 short period of time, as desired.

From this description, taken in connection with the drawings, it will be evident that I have accomplished all the objects herein stated and have provided a cheap and effective electrical alarm for timepieces.

I claim—

1. The combination with a timepiece, of a contact-ring mounted on the dial thereof, an alarm-hand rotatably mounted on the dial 15 and carrying a contact-spring to engage the contact-ring; a point carried by one of the clock-hands to depress said spring, and an electric circuit including an alarm, and having as its terminals, the contact-ring and contact-spring.

2. The combination with a timepiece, of an insulated contact-ring mounted on the dial thereof, an alarm-hand adjustably mounted on the dial; a spring carried by said 25 alarm-hand adapted to contact the insulated ring, means for causing engagement of the

spring and insulated ring, and an alarm-circuit in connection with the spring and ring.

3. The combination with a timepiece, an insulated ring mounted on the dial thereof, 30 an alarm-hand adjustably mounted on the dial, of a spring carried by said alarm-hand adapted to contact the ring, means carried by one of the clock-hands to depress said spring, and an alarm-circuit having as its terminals, 35 the ring and spring.

4. The combination with the dial of a timepiece, of an insulated contact-ring centrally mounted thereon, an alarm-hand rotatably mounted on the dial, a spring carried 40 thereby adapted to contact the insulated ring, clock-hands passing over the dial, an insulated point on one of the clock-hands adapted to depress the contact-spring, and an electric alarm-circuit included between 45 the contact-spring and insulated ring.

In testimony whereof I affix my signature in presence of two witnesses.

LOUIS TREDE.
